UNITED STATES PATENT OFFICE.

MICHAEL H. TOOMEY, OF GLENHAZEL, PENNSYLVANIA.

SAW-HANDLE.

No. 835,584.

Specification of Letters Patent.

Patented Nov. 13, 1906.

Application filed May 6, 1905. Serial No. 259,172.

To all whom it may concern:

Be it known that I, MICHAEL H. TOOMEY, a citizen of the United States, residing at Glenhazel, in the county of Elks and State of Pennsylvania, have invented a new and useful Saw-Handle, of which the following is a specification.

This invention relates generally to saw-handles, and particularly to one of that class of handles that are employed in connection with crosscut-saws driven by two operators.

The object of the invention is to provide a novel form of fastener which shall be positive in holding the saw-blade against loosening or separation therefrom, and in which disconnection of the handle from the saw will readily be effected when desired.

With the above and other objects in view, as will appear as the nature of the invention is better understood, the same consists in the novel construction and combination of parts of a saw-handle, as will be hereinafter fully described and claimed.

In the accompanying drawings, forming a part of this specification, and in which like characters of reference indicate corresponding parts, Figure 1 is a view in elevation exhibiting the handle of the present invention combined with a portion of the saw. Fig. 2 is a view in elevation, partly in section, showing more particularly the interior construction of the saw-blade-locking mechanism. Fig. 3 is a perspective detail view of a slightly-modified form of saw-engaging shank. Fig. 4 is a perspective detail view, partly in section, of the socket.

The implement of the present invention embodies a handhold 1, of the usual or any preferred construction, a socket 2, and a split saw-engaging shank 3.

The socket 2 is provided at one end with one of the shank-locking members, the same consisting of an annular inclined end or locking-face 4. The other locking member 5 is carried by the shank 3, and has a volute cam-locking face 6, which coacts with the like face of the locking member 4 to effect longitudinal draft upon the shank to cause it to bind the saw S against the outer end of head of the socket. The locking member 4 is, by preference, integral with the socket, although, if preferred, it may be made as a separate element and secured thereto.

In the form of the invention shown in Fig. 2 the locking member 5 is integral with the shank 3; but in the form of the invention

shown in Fig. 3 the locking member 5 is provided with a threaded orifice, which is engaged by the threaded stem 8 of the shank, the projecting end of the stem being upset or headed to prevent separation of the two members in use.

The shank 3 may be made of any suitable material, preferably of malleable cast-iron, with which in the form of the invention shown in Fig. 2 the locking member is cast integral and is provided with a longitudinal orifice or slot 9 to receive the terminal of the saw, as clearly shown in Fig. 2. The slot 9 will in practice be made of sufficient length to receive saw-blades of different widths, thereby to extend the range of utility of the implement. Instead of having the shank cast, as shown in Figs. 2 and 3, it may be constructed of a piece of metal bent upon itself, the deflected members being spaced apart a sufficient distance to form a slot to receive the blade.

The lower end of the handhold, as usual, is reduced to fit in the socket, thus to obviate the presentation of a shoulder or projection at the point of juncture of the parts, and to prevent accidental separation thereof a rivet or pin 10 may be passed through suitable orifices in the socket and through the reduced end of the handhold. (Shown in Fig. 2.)

In the use of the implement the saw is inserted through the slot 9 of the shank, and the handle 1 is grasped in one hand, and the free end of the shank is pressed against the other hand or against some fixed object. As a result the socket 2 will be slid longitudinally upon the shank until it comes in contact with the saw. The handle 1 can then be rotated practically without friction until the annular inclined end face thereof comes into contact with the corresponding face of the member 5, whereupon the socket end will be caused to bind tightly against the saw. The adjustment of the shank and socket against the edges of the saw is thus greatly facilitated and said parts can be caused to bind upon the saw by making less than one rotation on the socket. When the locking-faces are tightly wedged together, they will be positive in holding the shank against loosening, thereby effecting a stable juncture between the handle and the saw. To remove the saw, it will only be necessary to turn the handhold in the opposite direction to that turned in tightening the shank, whereupon the coac-

tion between the locking-faces will cause the shank to be projected beyond the socket, and thus release the blade.

The construction herein shown, while exceedingly simple, will be found thoroughly effective in use for the purposes designed, and will in a positive manner hold the blade against any tendency to work loose or to wabble within the clamp.

Having thus described the invention, what is claimed is—

1. A saw-handle embodying a socket provided at one end with an annular inclined end constituting a locking-face, and a longitudinally-slotted saw-engaging shank carrying a head adapted to fit snugly within the socket and provided with an annular inclined end locking-face to coact with that of the socket said shank and its head being slidable longitudinally within the socket to facilitate the adjustment.

2. A saw-handle embodying a socket provided at one end with an annular inclined end constituting a locking-face, and a longi-

tudinally-slotted saw-engaging shank carrying a detachable head adapted to fit snugly within the socket and provided with an annular inclined locking-face to coact with that of the socket said shank and its head being slidable longitudinally within the socket to facilitate the adjustment.

3. A saw-handle comprising a socket having an annular inclined end constituting a locking-face, a longitudinally-slotted saw-engaging shank slidable longitudinally within the socket and carrying a head provided with an annular inclined end constituting a locking-face, said faces adapted to coact subsequent to the longitudinal movement of the shank within the socket.

In testimony that I claim the foregoing as my own I have hereto affixed my signature in the presence of two witnesses.

MICHAEL H. TOOMEY.
